UNITED STATES PATENT OFFICE.

SIDNEY D. KING, OF PITTSTON, PENNSYLVANIA.

DUMPING-CAR.

SPECIFICATION forming part of Letters Patent No. 278,343, dated May 29, 1883.

Application filed March 27, 1883. (No model.)

To all whom it may concern:

Be it known that I, SIDNEY D. KING, of Pittston, in the county of Luzerne and State of Pennsylvania, have invented certain new and useful Improvements in Portable Hoppers and Doors therefor; and I do hereby declare the following to be a full, clear, and exact description of the invention, such as will enable others skilled in the art to which it appertains to make and use the same.

My invention relates to an improvement in coal or grain cars, the object of the same being to provide a car of this character constructed with double hoppers, and to provide doors for said hoppers which shall be automatic in their movements, which shall be so braced as to prevent all possibility of being forced open by the weight or pressure of the load, and so arranged as to depend no lower when open than when closed, thus allowing the hoppers to be built much deeper than in cars of ordinary construction; and with these ends in view my invention consists in certain novel features of construction and combinations of parts, as will be hereinafter fully set forth, and pointed out in the claims.

In the accompanying drawings, Figure 1 is a view in side elevation of a dumping-car embodying my invention. Fig. 2 is a plan view of the same. Fig. 3 is a reverse plan view. Fig. 4 is a detached view, showing the doors in their open position.

My improved car is transversely divided into two compartments, A, by the partition-wall B, which is composed of two sections, C and D, which meet at the top and diverge toward the bottom a certain distance, and then running parallel to the bottom of the car-frame, the vertical parallel portions forming the upper end walls of the hoppers E. The two sections C and D, being thus placed at an angle with each other, tend to deflect the contents of the car into the said hoppers. The floors of the said compartments are composed of the inclines F and G, which commence at the partition B and extend longitudinally nearly the length of the compartment. These inclines are similar to the faces of the partition B in so far as the deflection of the contents of the car is concerned, and also in that the lower vertical portions form the walls of the hoppers E. The floors of these hoppers extend from the ex-

treme ends of the car-body, have one continuous pitch, and are much deeper than hoppers of ordinary construction. At the lower ends of these hoppers, and at an angle with the vertical sections of the partition B, are the doors H. It will be readily seen that, owing to the construction of the hoppers E, the weight or pressure on the doors will be but a small fraction of that on the old style of car, and that the liability to be forced open when loaded, so great with bottom-door cars, is in this case greatly lessened.

I represents a beam running longitudinally through the center of the car, passing through the partition B, and secured to transverse end beams, J. On either side of the said beam I, parallel with and midway between the same and the outer beams, K L, are the beams M N, also secured to the said end beams, J, in any desired manner. To the said beams M is secured one end of the metal straps J', which pass around the hoppers E, and at the other end are fastened to the beams N. These straps, being secured to the hoppers and the beams, serve to relieve the former of a portion of the weight or pressure of the load within them.

Two transverse beams, O and P, are placed equidistant from the center of the car, and are secured to the longitudinal beams K and L, and strengthened by braces Q and R. These beams O and P are provided with hinges S and T, to which the upper sides of the doors H are fastened. To the lower sides of said doors H are hinged the arms U, the inner ends of which are hinged to a cross-bar, V. Depending slotted standards W are firmly secured to the beams M and N, the slots X in said standards forming guideways for the trunnions Y, projecting from the ends of the cross-bar V.

Z is a plate bolted or otherwise firmly secured to the brace Q. A hole or perforation passing through said plate Z and brace Q forms a bearing for the outer end of the shaft A', which passes transversely beneath the car-frame, the inner end of said shaft being supported in depending bearings B' C', secured to the beam I. On the shaft A', between the bearings B' C', is rigidly secured a pinion, D', which meshes with a rack-bar, E', rigidly bolted or otherwise firmly secured at the lower end to the middle of the cross-bar V, the upper

end of said rack-bar passing through a hole or perforation in the beam I.

To the plate Z and to one side of the shaft A' is pivoted a pawl, F', adapted to engage with the ratchet G', which is mounted on the outer end of the shaft A'. A cam, H', pivoted to the plate Z, is adapted to lock the pawl F' in position when in engagement with the said ratchet G'. On the opposite side of the shaft, 10 on the plate Z, is pivoted another pawl, I', also adapted to be engaged with the ratchet G', as will be hereinafter explained.

K' is a projection or stop, against which the pawl I' rests when out of engagement with the ratchet G'. 15

It will be readily seen that by my improved construction of doors great strength is obtained, the arms U acting as braces to keep the doors in their closed adjustment. When 20 the car is loaded the parts are in the positions shown in Fig. 1. When it is desired to dump the coal or ore it is simply necessary to turn the cam H' and lift the pawl F', the weight or pressure of the load against the doors forcing 25 the same open. This movement forces the lower sides of the doors toward the depending standards W, thus, through the intervention of the hinged arms U, elevating the cross-bar V, which is guided by the projecting trunnions 30 traveling in the slots X of the depending standards. This upward movement of the cross-bar V turns the shaft A' by means of the pinion D', secured to said shaft, and the rack-bar E', secured to the cross-bar V. The pawl I', when 35 resting against the projection or stop K', being in nearly a vertical position, is, by the jar of the falling coal, shaken from the pin, and falls by gravity against the ratchet G', and, engaging with the same, prevents the doors from 40 closing; or, immediately before unloading, it can be pushed down against said ratchet and the same result accomplished. When the car is entirely emptied the pawl I' is raised, and the weight of the rack-bar, together with that 45 of the cross-bar and doors, closes said doors automatically, and the car is ready to be re-loaded.

It will be observed that the doors work automatically; that, no chains being used, the 50 breaking of such in winter—a very great objection to the present style of doors in use—is entirely avoided, and that, owing to the construction of the operative parts, the doors, when open, hang no lower than when closed, 55 thus allowing the hoppers to be constructed much deeper than in the present style of cars.

My improved hoppers and doors are adapted to be applied to any style of car, are adapted for use in granaries, and may be used with a 60 single door. When an ordinary box-car is fitted with my improved style of hoppers and doors, trap-doors could be used to raise up, and thus present a smooth floor for ordinary freight. When used on flat-bottom cars the shaft A' is hung lower, so that the top of the 65 rack-bar will not penetrate the floor of the car.

In view of the many changes which might

be made in my improved device without departing from the spirit of my invention, I would have it understood that I do not limit myself to the exact construction of parts herein shown and described, but consider myself at liberty to make such slight changes and alterations as fairly fall within the spirit and scope of my invention. 70

Having fully described my invention, what I claim as new, and desire to secure by Letters Patent, is—

1. The combination, with a car-body divided transversely into two compartments, each provided with an inclined hopper arranged beneath the car, of doors and mechanism whereby said doors are opened by the weight of the contents of the car and closed by gravity. 80

2. The combination, with a car-body divided transversely into two compartments, each provided with a hopper, of doors pivotally secured at their upper ends for closing the said hoppers, arms hinged at one end to the doors and at the other end hinged to the cross-bar, said cross-bar being provided at each end with a trunnion and depending slotted standards adapted to guide said cross-bar in its movements, and means whereby said cross-bar may be raised or lowered. 85

3. The combination, with a car-body divided transversely into two compartments, each provided with a hopper, of doors pivotally secured at their upper ends for closing said hoppers, arms hinged at one end to the lower sides of the said doors, and at the other end hinged to a cross-bar provided at each end with a trunnion, depending slotted standards adapted to guide said cross-bar in its movements, and a horizontal shaft and intervening mechanism, 100 whereby said doors may be opened or closed simultaneously, substantially as set forth. 105

4. The combination, with a car-body divided transversely into two compartments, each provided with a hopper, of doors pivotally secured at their upper ends for closing said hoppers, arms hinged at one end to the lower side of said doors, and at the other end hinged to a cross-bar provided at each end with a trunnion adapted to travel in guides formed in depending standards, and a horizontal shaft provided on its inner end with a pinion adapted to mesh with a rack-bar secured to said cross-bar, substantially as set forth. 115

5. The combination, with a car-body divided transversely into two compartments, each provided with a hopper, of doors pivotally secured at their upper ends for closing said hoppers, arms hinged at one end to the doors, and at the other end to a cross-bar provided at each end 120 with a trunnion adapted to travel in guides formed in depending standards, and a horizontal shaft provided on its inner end with a pinion adapted to mesh with a rack-bar secured to the cross-bar, and provided on its outer end 125 with a ratchet adapted to be engaged by a pawl, as set forth. 130

6. The combination, with a car-body divided transversely into two compartments, each pro-

vided with a hopper, of doors pivotally secured at their upper ends for closing said hoppers, a horizontal shaft and intervening mechanism whereby said doors may be opened or closed simultaneously, and a plate secured to car-frame, provided near one end with a pawl to engage with a ratchet secured to the outer end of said shaft, and a cam to lock said pawl in position, said plate being also provided near 10 its opposite end with a second pawl to engage with said ratchet, and a stop against which the latter pawl rests when not in engagement with said ratchet, substantially as set forth.

7. The combination, with a car-body divided 15 transversely into two compartments, each provided with a hopper, of doors pivotally secured

at their upper ends, arms hinged at one end to the lower side of said doors, and their inner ends hinged to a cross-bar, and a shaft provided on its inner end with a pinion adapted 20 to mesh with a rack-bar secured to said cross-bar, said shaft being provided on its outer end with a ratchet adapted to be engaged by pawls, substantially as set forth.

In testimony whereof I have signed this 25 specification in the presence of two subscribing witnesses.
